PROTECTIVE AND LABEL-RETAINING CAP FOR THE TAP FITTING OF A BEER BARREL OR THE LIKE

Ernest R. Goll, Milwaukee, Wis., assignor to Braun-Goll Company, Milwaukee, Wis., a corporation of Wisconsin

Application June 7, 1955, Serial No. 513,689

4 Claims. (Cl. 220—24)

This invention relates to a protective and label-retaining cap for the tap fitting of a beer barrel or the like.

The cap is desirably made of plastic or elastomeric material sufficiently flexible and sufficiently yieldable to be molded with a rib disposed internally of the lower margin of its skirt portion for engagement with the flange of the cap fitting. An overhanging flange at the top of the cap engages the inner margin of a label about an aperture therein through which the skirt portion of the cap is received.

In the drawings:

Fig. 1 is a top perspective view of a cap embodying the present invention.

Fig. 2 is a bottom perspective view of the cap.

Fig. 3 is a plan view fragmentarily illustrating the top of a barrel to which a label and the cap of the present invention have been applied.

Fig. 4 is a view taken in cross section on the line 4—4 of Fig. 3.

The barrel shown is of generally conventional design having a top portion 5 provided with a tap bushing 6 welded thereto. The tap bushing 6 has a recess 7 from the center of which there arises an annular stud 8 having projecting flanges at 9 and 10 with arcuate outer margins. The central opening 11 receives a cork or plug 12 which must be withdrawn when the barrel is tapped. The tap rod forms no part of the present invention. It is introduced through the opening 11 and has flanges which engage flanges 9 and 10 to lock the rod in place during use.

In accordance with the present invention, a label 15 bearing the brewer's advertising is made in such dimensions that it spans the recess 7 and has a central opening at 16 slightly larger in diameter than the combined extent of flanges 9 and 10. The cap 20 is desirably molded in one piece of a flexible and elastic plastic or elastomeric material to provide the cap top 21 and a depending skirt 22 beyond which a flange portion 23 of the top projects to engage the margin of the label about the opening 16 therein. The skirt is received through opening 16 as clearly shown in the drawings.

On the under side of the top wall 21 of the cap, I desirably provide some relatively deep ribs extended over such top wall as shown at 24. These rest on the top of the stud 8 and the flanges 9 and 10 thereof and they project over the notches between such flanges to provide ducts through which air can circulate over the top of the stud to dry up any liquid which may have spilled thereon. The central portion of the top wall is desirably raised somewhat at 25 to accommodate any reasonable extent to which the plug or cork 12 may project above the stud.

Integral with the skirt 22 adjacent its lower margin is a series of circumferentially spaced inwardly projecting

2

protuberances 27 which engage beneath the flanges 9 and 10 of the stud to hold the cap in place. A continuous annular rib may take the place of protuberances 27. The elasticity of the plastic is sufficiently great to permit the molded cap to be withdrawn from its core without destruction of the core and to permit the skirt portion of the cap to spring over the flanges 9 and 10 of the stud and to resiliently engage beneath the margins thereof as the cap is applied.

10 The cap will materially protect the stud and the crevice about the plug or cork from dirt and, together with the label 15, it will cover the entire recess 7 to exclude dirt therefrom. Yet sufficient circulation of air over the surface of the stud is accommodated between the rib 24

15 so that any liquid is dried up.

An incidental feature of the invention consists in its capacity to hold securely in place on the barrel a label apertured to receive the skirt portion 22 of the cap, whereby the label need not be cemented or otherwise 20 adhered to the barrel and is readily moved in one piece therefrom when the cap is withdrawn.

25 While any elastomeric material may be used, including elastically yieldable plastic, it is also possible for some purposes to employ relatively inelastic plastic such as "nylon." The particular materials preferred are polyethylene or butyrate acetate. Other elastic plastics are polyvinyl or vinyl or high impact styrene. Another material usable under some circumstances is the product known as "Teflon" which comprises tetrafluoroethylene. 30 An example of a non-plastic elastomeric is the synthetic rubber known as neoprene.

I claim:

1. In combination, a container tap bushing having an annular top surface and an inwardly offset portion providing a recess and having an annular tap stud disposed centrally in the recess and having a flange overhanging the recess, an annular label overlying the top surface and having a central aperture slightly larger in diameter than the overall dimension of said flange, a plug removably closing the tap stud, and a cap of elastic material having a depending skirt passing through the aperture of the label and about the flange of the tap stud in protective relation to the plug, said skirt having means engaged with the top stud flange to retain the cap, said cap further being provided with an annular flange overhanging marginal portions of the label about the aperture therein for anchoring the label to said annular surface.

2. The device of claim 1 in which said cap has a raised central portion clearing said plug and is provided 50 in annular series about said raised central portion with inwardly projecting generally radial ribs affording ducts for air circulation beneath said cap.

3. The device of claim 1 in which said means comprises an annular series of protuberances extending about 55 the interior of the skirt at a point spaced below said top surface.

4. In combination, a container having a tap bushing having an inwardly offset portion providing a recess and 60 having a tap stud disposed centrally in the recess, a label overlying the bushing and having an inner peripheral portion projecting over the recess and a central aperture registering with said stud, a cap of elastic material having a portion extending through said aperture to close 65 said aperture and including a skirt elastically embracing the stud and further having a portion overhanging marginal portions of the label about its aperture for anchoring the label to the bushing.
